UNITED STATES PATENT OFFICE.

EDWARD S. RIDEOUT, OF KLAMATH FALLS, OREGON, ASSIGNOR OF ONE-HALF TO
HAROLD D. MORTENSEN, OF KLAMATH FALLS, OREGON.

OFFSET FOR LOG CARRIAGES.

Application filed August 15, 1922. Serial No. 581,919.

To all whom it may concern:

Be it known that I, EDWARD S. RIDEOUT, a citizen of the United States, residing at Klamath Falls, county of Klamath, and 5 State of Oregon, have invented new and useful Improvements in Offsets for Log Carriages, of which the following is a specification.

This invention relates to saw mill machinery, and particularly pertains to an offset mechanism for log carriages. It is the principal object of the present invention to provide automatically operating means for moving a log carriage laterally toward and 15 away from the plane of a saw, by which a log carried by the carriage is to be cut.

The present invention contemplates the use of a log carriage adapted to travel on a track, and which carriage has a frame laterally movable relative to the running gear of the carriage, being fitted with automatically operating means for shifting the carriage frame in alternate directions relative to the running gear as the carriage is moved 25 back and forth along its track.

The invention is illustrated by way of example in the accompanying drawings, in which:

Fig. 1 is a view in plan showing the complete invention.

Fig. 2 is a view in end elevation showing the carriage with a log mounted thereon.

Fig. 3 is an enlarged fragmentary view in side elevation showing the actuating means for the trip mechanism of the carriage.

Fig. 4 is a fragmentary view in plan showing a portion of the actuating means shown in Fig. 3.

Referring more particularly to the drawings, 10 indicates rails on which the log carriage 11 is intended to travel. This carriage is provided with a running gear constituting a plurality of axles 12 supported 40 in suitable journal boxes 13 beneath a frame 14. The axles are slidable through the journal boxes and are fitted at their opposite ends with wheels 15 and 16. The wheels 16 are preferably formed with opposed 45 flanges around their circumferential faces, while the faces of the wheels 15 are flat.

The frame 14 may be of any design and construction, although here shown as being formed with a pair of parallel girders 18 50 connected by transverse beams 19. The

frame is intended to support a log as shown at 20 and to permit the log to be cut lengthwise by means of a band or other saw not shown in the drawings.

It is the principal object of the present invention to provide automatically operating means to intermittently shift the frame laterally of the track and thus to move the log away from the saw as it is being drawn back for a new cut and to move the log over when this cut is about to be made. The means for producing this result comprise an air or steam cylinder 21 which is secured to an extension frame 22 of the carriage. This cylinder is fitted with a piston 23 provided with a piston rod 24. The piston rod in the present instance is parallel with the track and is fitted with an operating lever 25. This lever is pivoted intermediate its ends to a pivotal mounting 26 carried by the frame structure 22. The opposite end of the lever 25 from the piston is connected with a rod 27 also extending parallel with the track. The ends of this rod are secured to bell crank levers 28 and 29. These levers are pivotally mounted at their ends upon brackets 30 carried by the frame of the carriage. It is to be understood that the long arms of the levers are parallel, extending transversely of the carriage, while the short arms extend substantially longitudinally of the carriage and are pivotally connected to sleeves 31. These sleeves are mounted upon certain of the axles 12 and are disposed between fixed collars 32 and 33. These collars are split and are threaded onto the axles, thus making it possible to readily adjust them relative to the axles to insure a predetermined stroke.

The cylinder 21 is provided with ports 34 and 35 at its opposite ends, which ports may be alternately opened by a sliding valve member 36. The sliding valve is connected with a lever 37 pivoted to the carriage frame at 38. The free end of this lever extends inwardly toward the body of the carriage and is secured to a connecting rod 39 leading to a bell crank 40. The bell crank 40 is pivoted upon a pin 41 held by a bracket 42 on the carriage frame. The horizontal leg of this bell crank is provided with a depending connecting rod 43 which is pivoted to a shaft 44. This shaft extends through a vertical opening in a bracket 45 and is secured at its lower end to a shoe 46. The

shoe 46, as more clearly shown in Fig. 4 is formed with opposite bevelled sides, substantially agreeing with the bevelled faces of the opposite flanges of a carriage wheel 16 between which flanges the shoe is positioned. A guide plate 47 is secured to the back of the shoe and may move vertically through openings in horizontal arms at the top and bottom of the hanger 45.

10 A plurality of springs 48 force against the back of the shoe 46 and produce continuous frictional engagement between the faces of the shoe and the flange faces of one of the pulleys 16. Thus when the wheel 15 16 is rotated in either direction it will cause the shoe to be shifted in the same direction and will thereby act through the levers and links to move the sliding valves 36.

In operating of the present invention the 20 device is assembled as here shown. Assuming that a cut has been made and that the carriage is now being moved in the direction of the arrow —a—, the operation will be as follows: Rotation of wheel 16 in engagement with the shoe 46 will cause this 25 shoe to move downwardly in the direction of arrow —b— as shown in Fig. 4. This will pull on the connecting rod 43, causing the bell crank 40 to swing in the direction of the arrow —c—. This motion will be imparted through the rod 39 and the lever 37 to the valve 36. This will uncover port 21, thus acting to force the piston 23 outwardly in the direction of the arrow —d—. The 30 outward movement of the piston will act through lever 25 and the connections 27 to swing shifting bell cranks 28 and 29 in the direction of the arrow —e—. This will act to shift the frame laterally and in the direction of arrow —f—. This valve will be held over all the time the carriage is being moved in the direction of the arrow —a—, but when it is moved in the opposite direction the frictional engagement of the 35 wheel 16 with the shoe 46 will cause this shoe to shift in an opposite direction from the arrow —b—, thus setting in motion the lever mechanism which will move the valve member 36 in a direction to close the port 21 and open the port 20.

It will thus be seen that the movement of the carriage in opposite directions will alternately cause the log to be offset by a simple and effective operation.

55 While I have shown the preferred form of my invention as now known to me, it will be understood that various changes might be made in the combination, construction and arrangement of parts by those skilled in the art without departing from the spirit of the invention, as claimed.

Having thus described my invention, what I claim and desire to secure by Letters Patent is:

65 1. An offset mechanism for a log carriage

comprising a carriage frame, transverse axles upon which said carriage frame is mounted and upon which it is slidably laterally, flange wheels on said axles to run upon a track, sleeves fixed on said axles, bell crank levers pivoted to the carriage frame and each having one arm connected with one of said sleeves, a rod connecting the other ends of said bell cranks, a steam cylinder having a piston with a piston rod, an operating lever centrally pivoted to said carriage frame, one end of said lever being connected with the said piston rod, the other end being connected to the rod connecting said bell crank arms whereby movement of the piston will shift the frame laterally on said axles, a valve controlling the inlet ports of said steam cylinder, and an operative connection between said valve and one of the wheels on said axles whereby movement of the wheel in one direction will actuate the valve to admit steam into one end of the cylinder to cause the carriage frame to be shifted in one direction and movement of the wheel in the opposite direction to actuate the valve to admit steam in the other end of the cylinder to shift the frame laterally in the opposite direction.

2. An offset mechanism for a log carriage comprising a carriage frame, transverse axles upon which said carriage frame is mounted and upon which it is slidably laterally, flange wheels on said axles to run upon a track, sleeves fixed on said axles, bell crank levers pivoted to the carriage frame and each having one arm connected with one of said sleeves, a rod connecting the other ends of said bell cranks, a steam cylinder having a piston with a piston rod, an operating lever centrally pivoted to said carriage frame, one end of said lever being connected with the said piston rod, the other end being connected to the rod connecting said bell crank arms whereby movement of the piston will shift the frame laterally on said axles, a valve controlling the inlet ports of said steam cylinder, and an operative connection between said valve and one of the wheels on said axles whereby movement of the wheel in one direction will actuate the valve to admit steam into one end of the cylinder to cause the carriage frame to be shifted in one direction and movement of the wheel in the opposite direction to actuate the valve to admit steam in the other end of the cylinder to shift the frame laterally in the opposite direction, said operative connection comprising a shoe frictionally geared against the face of said wheel and adapted to be shifted longitudinally by turning movement of the wheel, a bell crank pivoted to the carriage frame, one arm of said bell crank being connected to said shoe, the other arm being connected by means of levers to said valves.

3. An offset mechanism for a log carriage comprising and including a carriage frame, transverse axles upon which said carriage frame is mounted and upon which it is slid-
5 able laterally, flanged wheels on the axles adapted to run upon a track, pairs of collars adjustably mounted upon said axles, a sleeve between each pair of collars, sleeves be-
tween said pairs of collars to move the car-
10 riage frame a greater or less distance lat-
erally to fit the thickness of the cut from the
log on the carriage frame, bell crank levers
pivoted to the carriage frame each having
an arm connected with one sleeve, a rod
15 connecting the ends of the other arms of the
bell cranks, an operating lever centrally piv-
oted to the frame, one end of said lever con-
necting with said rod, a steam cylinder hav-
ing a piston with a piston rod, the other
end of said operating lever being connected 20
to said piston rod whereby movement of
the piston in the said cylinder will longi-
tudinally shift the first named rod to lat-
erally move the frame through the medium
of the bell cranks, a slide valve controlling 25
the ports of said cylinder, an operable con-
nection between said slide valve and one of
the wheels on said axles whereby turning
movement of the wheel will control said
slide valve to cause lateral shifting of the 30
carriage frame in opposite directions.

EDWARD S. RIDEOUT.
